CLAIM

The ornamental design for a flashlight with mount, as shown and described.

DESCRIPTION

FIG. 1 is a perspective view of a flashlight with mount; FIG. 2 is a front view of the flashlight with mount of FIG. 1;

FIG. 3 is a back view of the flashlight with mount of FIG. 1;

FIG. 4 is a right view of the flashlight with mount of FIG. 1;

FIG. 5 is a left view of the flashlight with mount of FIG. 1; FIG. 6 is a top view of the flashlight with mount of FIG. 1; FIG. 7 is a bottom view of the flashlight with mount of FIG. 1; and,

FIG. 8 is a perspective view of the flashlight with mount of FIG. 1, attached to a spray bottle head shown in broken lines as environmental subject matter.

The broken lines shown in the drawings represent portions of the flashlight with mount that form no part of the claimed design. The additional broken lines shown in FIG. 8 represent environmental subject matter that forms no part of the claimed design. The dash-dot-dash lines shown in the drawings demarcate the boundary of the claimed design.
